UNITED STATES PATENT OFFICE.

JOHN F. WOLLENSAK, OF CHICAGO, ILLINOIS.

TRANSOM-LIFTER.

SPECIFICATION forming part of Letters Patent No. 310,352, dated January 6, 1885.

Application filed August 18, 1884. (No model.)

To all whom it may concern:

Be it known that I, JOHN F. WOLLENSAK, a citizen of the United States, residing at Chicago, in the county of Cook and State of Illinois, have invented certain new and useful 5 Improvements in Transom-Lifters, of which the following is a specification.

It has been objected to transom-lifters as heretofore constructed that where a long operating-rod is used it is liable to become bent at its lower end or at a point below the lowest guide by the weight of the transom or by carelessness in handling. I propose to overcome this difficulty by sleeving a hollow operating-rod upon a long stationary guide-rod, whereby 15 the former is supported throughout its entire length, thus obviating all danger of the bending of either of said rods. This construction also enables the making of transom-lifters of 20 any length, on short notice, out of material at all times readily obtained, and without the necessity of having special castings therefor.

In the accompanying drawings, Figure 1 shows my improved lifter applied to a transom; and Fig. 2 is a perspective view of the 25 transom-lifter detached, the operating-rod being broken away at one point to show the guide-rod.

A is the guide-rod, which is stationary, and 30 connected to the casing by suitable brackets, as *a a*. This guide-rod is made enough longer than the operating-rod to permit the latter to travel thereon a sufficient distance to open the transom to its widest extent. The guide-rod 35 may be made entire or in two pieces; but in the latter case the free ends are at all times confined by the operating-rod. The operating-rod B is made from a tube or hollow rod, and wholly or partially surrounds the guide-rod A, on which it travels. This operating-rod 40 is connected through suitable means—such as the ear-pieces *b b*—to a lifting-arm, D, the latter being in turn connected to the transom. An additional guide for supporting and lock-

ing the operating-rod is also shown in the 45 drawings. This guide E may consist of a block having a central aperture sufficient in size to permit the insertion of the operating-rod through it, and is provided with screw-flanges *e e*. It is also provided with a set-screw, F, or other suitable locking device, and it may be located at any convenient point between the ends of the guide-rod. More than one of these guides E may be used when made necessary by the length of the device. A 50 thumb-piece, G, at the lower end of the operating-rod furnishes means whereby said rod is easily handled while operating. The transom 55 may be hung either at the top, bottom, or center.

As the operating-rod has substantially a continuous bearing upon the guide-rod from the point of junction of the lifting-arm to the thumb-piece, the danger of the weight of the transom bending the operating-rod is entirely 60 obviated, and in this my invention is an improvement upon the ordinary transom-lifter, in which the guide-rod is not inclosed or embraced by the operating-rod.

I do not claim, broadly, a transom-lifter in 70 which the operating-rod is connected with the guide-rod by devices, such as an eye; but my invention is limited more particularly to a construction in which the operating-rod is sleeved and has a continuous bearing on the 75 guide-rod throughout the whole or greater part of its length.

I claim—

A transom-lifter having in combination a stationary guide-rod, an operating-rod wholly 80 or partially surrounding the guide-rod and having a continuous bearing thereon, and a lifting-arm, substantially as and for the purpose set forth.

JOHN F. WOLLENSAK.
